[57] **CLAIM**

The ornamental design for a brick mold, as shown and described.

DESCRIPTION

FIG. 1 is a perspective view of the brick mold;
FIG. 2 is a top view thereof;
FIG. 3 is a front view thereof;
FIG. 4 is a side-edge view thereof, the other side being identical thereto;
FIG. 5 is a bottom view thereof; and,
FIG. 6 is a rear view thereof.
The brick mold is broken in the center to disclose indeterminate length.
